APPARATUS FOR ASSEMBLING RESILIENT JOINTS

Otto E. Hermanns, Akron, Ohio, assignor to The B. F. Goodrich Company, New York, N. Y., a corporation of New York

Application May 31, 1943, Serial No. 489,203

4 Claims. (Cl. 29—88.2)

This invention relates to the assembling of resilient joints, such for example as those of the track units of an endless track for self-laying track type vehicles, and is especially useful in the assembling in their housings of connecting pins or shafts having resilient torsion bushings secured thereto.

In the assembling of cross pins and torsion bushings with track blocks or units it is desirable to locate the cross pins rotatively in respect to the track units so as to provide uniform torsional deflection of the bushings in use, and is desirable also to locate the cross pins with respect to the track units so that the pins extend determinate amounts from the sides of the track units or blocks at opposite sides thereof.

The objects of the present invention are to provide means for forcing the cross pins with the torsion bushings thereon into the housings of the track blocks or units or other structure; to provide means for properly locating the cross pins with relation to each other and to the housing; to facilitate the rapid assembly of the cross pins and bushings with the housing; and to assemble simultaneously a plurality of cross pins and associated torsion bushings with a single track block.

These and other objects will appear from the following description and the accompanying drawings.

Of the drawings:

Fig. 1 is a front elevation of apparatus embodying one form of the invention, parts being broken away.

Fig. 2 is a side elevation thereof as viewed from the right side of Fig. 1, parts being broken away and parts shown in section,

Fig. 3 is a detail view of the upper cross head partially broken away and partly in section with the ends of a pair of cross pins engaged thereby,

Fig. 4 is a cross sectional view taken on line 4—4 of Fig. 2,

Fig. 5 is a detailed cross sectional view taken on line 5—5 of Fig. 1,

Fig. 6 is a plan view of a track block having cross pins and torsion bushings assembled therewith and indicating in broken lines at one end of the cross pins the position of the cross pins after the first pressing movement, the block being partially broken away and in section,

Fig. 7 is a diagrammatic view of the operating cylinders, their valves and limit switches, and

Fig. 8 is a side elevation of one of the solenoid operated valves.

Referring to the drawings which illustrate an embodiment of the invention, and first referring

to Fig. 6, a track block 10 is provided with a pair of parallel cylindrical cross passages 11, 12 through which extend the cross pins 13, 14, the pins being longer than the width of the block 10 so that their ends extend at each side thereof. Surrounding the pins within the cross passages and mounted under compression are torsionally resilient structures which may comprise a series of resilient torsion bushings 15, 16 which resist rotation of the pins with respect to the block. For this purpose the bushings which are of resilient vulcanized rubber or other rubber-like material, are formed about the pins and secured thereto as by a bond of vulcanization. The bushings are spaced longitudinally from each other as indicated in Figs. 1 and 2 where the cross pins are shown before being assembled with the track block. This spacing permits distortion of the bushings longitudinally under radial compression.

Each cross pin is provided with a flattened portion 17, 18, 19, 20, near its opposite projecting ends and the flats on the pins are so oriented as to be at an acute angle to the flats of an adjacent pin so as to engage a wedge member of a connecting link in the assembly of the track, the angle usually being at about 10 degrees to the perpendicular to the base of the track.

Referring to Figs. 1 and 2, the apparatus for assembling the cross pins with the track block 10 is mounted on a frame 30 surmounted by a bed plate 31. Fixed to the bed plate is a column 32 which supports a vertical double-acting fluid pressure operated cylinder 33 having a piston 34 fixed to a piston rod 35, and a cross head 36 is adjustably secured to the lower end of the piston rod 35 which is threaded as at 37 for adjusting its movement. The cross head is slideably mounted in vertical ways 38 fixed to the column 32. As seen in Fig. 2 the cross head 36 is formed with a pair of cylindrical vertically disposed sockets 40, 41 in which are slideably mounted a pair of chucks 42, 43 for holding and aligning the cross pins 13, 14. Each chuck is guided in its vertical movements by a cross pin 44, 45 respectively which cross pins are guided by slotted openings 46 in a cross head. Compression coil springs, such as 50, are mounted in the cross head between the cross head and the chucks, to normally force the chucks into the lowered position shown in the drawing. Each chuck has a cylindrical socket 51 for receiving the end of a cross pin and is slotted axially from one side of the chuck to a position near its center to receive a locating jaw 52 which is pivotally mounted on a pin 53 within the

slot. A compression coil spring 54 between the locating jaw and the chuck forces the lower end of the chuck jaw toward the cross pin and in contact with the flat 19, the jaw being formed with a clearance notch to clear the rounded portion of the pin beyond the flattened portion at the end thereof. An adjustable cam pin 60 extends through an aperture in the cross head 36 and engages a cam 69 which bears against a face of the jaw so that when the chuck is forced upwardly into the cross head the cam pin 60 forces the rocking locating jaw toward the flat on the cross pin, orienting the cross pin to the proper position. The two chucks are so arranged with respect to each other as to orient the pair of cross pins to the proper angular relation to each other. For locating the track block, a box-like jig 61 is fixed to the bed plate 31 below a cylinder 33. The back and vertical sides of the jig are stationary and are threaded to receive locating screws 62 which bear against the track block. A cross bar 63 is hinged, as at 64, to one of the vertical sides of the jig and is retained in place by a latch 65 (see Fig. 4) held in position by an extension coil spring 66. A pressure pad 67 is mounted on the cross bar and is forced by a compression coil spring 68 in a direction to engage the track block and hold it against the locating screws when the cross bar 63 is in its latched position.

For guiding the cross pins with relation to the track block and for radially compressing the resilient torsion bushings, a plate 70 is mounted above the vertical sides of the jig, and is held thereabove by compression coil springs 71, 72 (see Fig. 5). The plate 70 has dowel pins 73 which engage dowel holes in the vertical sides of the jig to confine movement to a vertical direction. The plate 70 is formed with a pair of funnel-like apertures 74, 75, the lower ends of which are of the same size and shape as the cross passages 11, 12 of the track block and the upper ends of which are as large in diameter as the uncompressed torsion bushings. The arrangement is such that when the cross pins are forced downwardly by the piston 34 the lowermost torsion bushings engage the funnel-like openings and force the chucks 42, 43 to an upper locating position and upon further downward movement of the piston the torsion bushings are radially compressed and guided into the track block.

For supporting the lower ends of the track block during the pressing movement, a movable anvil block 80 is slideably mounted for horizontal movement over the upper face of the bed plate 31, suitable guides 82 being provided on the bed plate for guiding it. The anvil block is controlled by a double acting fluid pressure operated cylinder 83 fixed to the bed plate and having a piston 84 fixed to a piston rod 85 which in turn is secured to the anvil. The arrangement is such that at the forward position the anvil is beneath the track block and when the anvil is withdrawn rearwardly in Fig. 1 or to the right in Fig. 2, the track block may drop to a lower position. For clearing the lower ends of the cross pins the anvil is formed with vertical slots 86, 87 open at the front of the machine as seen in Fig. 1 and of such size as to clear the cross pins.

It is desirable to press the torsion bushings and the cross pins in one direction to a point further than the final position, and then to press the cross pins in the opposite direction a slight

distance to overcome undue longitudinal distortion of the torsion bushings in one direction. For this purpose a double acting liquid pressure operated cylinder 90 is fixed to the bed plate on its lower face and has a movable piston 91 fixed to a vertical piston rod 92 which in turn is fixed to a vertically movable cross head 93. A pair of plungers 94, 95 are adjustably secured to the cross head and are arranged to extend vertically with their axes spaced apart and in alignment with the cross pins. For adjusting them vertically these pins have threaded engagement, as at 96, with the cross head 93. Guiding apertures for the plungers 94, 95 are provided through the bed plate 31, and the arrangement is such that in their lowered position the plungers are withdrawn below the upper face of the bed plate 31 where they clear the anvil 80 in its movements and in their raised position they engage the lower ends of the cross pins and force them upwardly to the desired final position. For resisting upward movement of the track block the sides of the jig are formed with outwardly turned flanges 100, 101 and the plate 70 is provided with end pieces 102, 103, having inwardly turned flanges engaging therebelow, the arrangement being such that limited vertical movement of the plate 70 under the influence of the coil springs 71, 72 and of the pistons 34 and 91 is permitted. The object of this is to relieve pressure on the anvil 80 when the piston 91 moves upwardly and at the same time to provide a positive abutment to resist upward movement of the piston 91.

For conveniently operating the apparatus the cylinder 33 is provided with pipes 110, 111 at its upper and lower ends respectively which are controlled by a four-way valve 112 which when turned in one direction connects the pipe 110 to a fluid pressure supply line 113 and connects the pipe 111 to the atmosphere, and when turned in the opposite direction connects the pipe 111 to the supply line 113 and connects the pipe 110 to exhaust to the atmosphere. Similarly the cylinder 90 is connected at its upper end by a pipe 114 and at its lower end by a pipe 115 controlled by a four-way valve 116, which in one position connects the pipe 114 to the fluid pressure line 113 and the pipe 115 to exhaust, and in the other position connects the pipe 115 to the fluid pressure line 113 and connects the pipe 114 to exhaust. Similarly cylinder 83 is connected by a pipe 117 at its forward end and by a pipe 118 at its rearward end to a four-way valve 119 which in one position connects the pipe 117 to the fluid pressure line 113 and the pipe 118 to exhaust and in the other position connects the pipe 118 to the fluid pressure line 113 and the pipe 117 to exhaust. Each of these valves 112, 116 and 119 is preferably of the solenoid operated four-way poppet valve type of which the valve 112 is illustrated in Fig. 8. While these valves may be operated individually from push button circuits by an operator, it is preferred to so connect these solenoids to limit switches located on the apparatus as to cause the various cylinders to operate in the desired order and complete the operations automatically. For this purpose the cross head 36 is provided with an adjustable stop 120 adapted at the lowermost position of the cross head to engage a limit switch 121 mounted on the column 32. The cross head 36 is started in its downward movement by a foot operated switch (not shown) which momentarily energizes solenoid 123 to shift valve 112 to a posi-

tion where fluid pressure is admitted through pipe 110. The limit switch 121 in closing energizes one of the solenoids 122 of the valve 112, thereby causing the piston 34 to be raised to its upper position by the fluid pressure admitted through pipe 111. At the same time the closing of the switch 121 energizes one of the solenoids 124 of the valve 116 and de-energizes the solenoid 125 thereby causing the piston 91 to raise so that the plungers 94, 95 engage the lower ends of the cross-rods and raise them to their final position with respect to the track blocks. The cross head 93 is provided with an adjustable stop 130 which at its uppermost position closes the limit switch 131 which energizes one of the solenoids 132 of valve 119 and de-energizes the solenoid 133 thereof thereby causing the anvil 80 to be retracted. When the anvil 80 is completely retracted, a stop 150 on the anvil engages a limit switch 151 which causes the solenoid 125 of the valve 116 to be energized and the solenoid 125 thereof to be de-energized causing the cross head 93 to return to its lowermost position. The cross head 93 is also provided with a second adjustable stop 140 which in its lowermost position is adapted to engage a limit switch 141 mounted on the cylinder 90, the closing of the limit switch 141 energizes the solenoid 133 of the valve 119 and deenergizes the solenoid 132 thereby causing the anvil 80 to be returned to its forward position.

The operation of the apparatus is as follows: With the piston 91 in its lower position, the piston 34 in its raised position and the piston 84 and consequently the anvil 80 in its forward position, as shown in Fig. 2, the operator places the track block 10 within the jig upon the anvil 80, the cross bar 63 being swung open to admit the track block. The operator then swings the cross bar 63 to its latched position thereby locating the track block in proper position. He then grasps the cross pins 13, 14 with the resilient torsion bushings mounted thereon, and inserts the upper ends of the cross pins in the chucks 42, 43 with their lower ends over the funnel-shaped guide openings in the plate 70. The operator then depresses the foot-operated limit switch, not shown, which energizes solenoid 122 and de-energizes solenoid 123 causing the cross head 36 to be lowered. The cross pins with the torsion bushings thereon are forced against the plate 70 lowering it into contact with the track block and into the track block to a position where they are advanced slightly beyond their normal position, whereupon by contact of the stop 120 with the limit switch 121 the valve 112 is reversed to raise the cross head 36, while simultaneously the solenoid 124 of the valve 116 is energized to raise the cross head 93. The plungers 94, 95 thereupon engage the lower ends of the cross rods and position them upwardly in the reverse direction to their normal position with relation to the track block, whereupon by contact of the stop 130 with the limit switch 131 the anvil 80 is retracted. At its retracted position the stop 150 on the anvil 80 contacts with the

limit switch 151 on the cylinder 83 causing the piston 91 to be lowered, which permits the assembled track block and cross pins to be lowered in the path of the anvil 80. Upon the return of the cross arm 93 to its lowermost position the stop 140 engages the limit switch 141 which causes the valve 119 to be reversed and the anvil 80 is forced forward engaging the track block and forcing it forward out of the jig, the cross bar 63, being frictionally latched, springs open under this movement, and the operator catches the track block and removes it from the apparatus.

The apparatus has the advantage that the torsion bushings are released from excessive longitudinal distortion in one direction and the flats on the cross bars are properly oriented with respect to each other in a single operation.

Variations may be made without departing from the scope of the invention as it is defined by the following claims.

I claim:

1. Apparatus for assembling a pin and resilient bushing in a housing, said apparatus comprising means for supporting a housing, means for supporting the cross pin and bushing in determinately oriented position, means for forcing the cross pin and bushing into the housing in one direction to a position beyond the normal position, and means for forcing the cross pin in the opposite direction to its normal position.

2. Apparatus for assembling cross pins and torsion bushings with track units, said apparatus comprising means for supporting a track unit, means for supporting the cross pins and bushings in determinately oriented position, means for simultaneously forcing the cross pins and bushings through the track unit in one direction to a position beyond the normal position, and means for forcing the cross pins in the opposite direction to their normal position.

3. Apparatus for assembling cross pins and torsion bushings with track units, said apparatus comprising means for supporting a track unit, means for supporting the cross pins and bushings in determinately oriented position, means for forcing the cross pins and bushings through the unit, means for withdrawing the supporting means from beneath the assembled track block, and means for returning the said supporting means to force the assembled track block from the apparatus.

4. Apparatus for assembling a pin member and a housing member with an interposed resilient bushing, said apparatus comprising means for telescopically forcing said members with the resilient bushing interposed therebetween by movement of one member relative to the other in one axial direction to a position beyond its normal assembled position with relation to the other and with said bushing axially loaded in said direction, and means for telescopically forcing said members and adjusting the axial loading by movement of one member relative to the other in the reverse axial direction to its normal assembled position with relation to the other.

OTTO E. HERMANNNS.
